ARC FURNACE WITH LIFT AND SWING
ASIDE ROOFWilliam E. Moore, Pittsburgh, Pa., assignee to
Delaware Engineering Corporation, Pittsburgh,
Pa., a corporation of Delaware

Application January 31, 1946, Serial No. 644,582

9 Claims. (Cl. 13—9)

1

This invention relates generally to an electric arc furnace and, more particularly, to an electric furnace having a roof of the lift-swing-aside type for top charging.

In the swing type of top charge electric furnace, the roof and the supporting structure for the electrode masts are lifted and swung to the side by suitable power means such as a vertical oil-hydraulic ram and cylinder, thereby uncovering the furnace crucible for charging purposes and the like.

In most top charge electric furnaces of the swing type, the means employed for causing side-wise movement or swing of the roof are generally complicated in design, expensive to manufacture, and rather difficult to maintain. This is primarily due to the fact that separate power actuators are used for effecting lifting of the roof and for effecting the swinging movement thereof, thus requiring careful attention and skill of the operator to coordinate these two movements.

An object of my invention is to provide an electric arc furnace of the swing type which is devoid of the above-named disadvantages of common types of such furnaces.

A more specific object of my invention is to provide a relatively simple and unitary power-actuator means for simultaneously effecting a lifting and swinging movement of the roof and electrode supporting structure of an electric arc furnace and requiring no special skill or alertness by the operator to coordinate these two movements.

A still more specific object of my invention is to provide a novel hydraulic ram and cylinder construction for lifting the roof of an electric furnace which structure incorporates cam means to simultaneously cause sidewise swinging movement of the roof and the electrode-supporting structure as such roof is being lifted.

Other objects and advantages will become apparent from a study of the following specification and drawings wherein:

Figure 1 is a plan view of an electric furnace embodying the principles of my invention wherein the full lines show the roof in its normal position, whereas the dash and dot lines show the roof swung aside;

Figure 2 is a side elevation of the furnace shown in Figure 1 as viewed from a plane parallel to the tilting plane from the cylinder side and showing the furnace in the upright position;

Figure 3 is a fragmentary cross-sectional view taken through the electrode gear and the furnace crucible at right angles to the tilting plane;

2

Figure 4 is an enlarged longitudinal sectional view of the ram and cylinder together with the associated structure shown broken away.

Figure 5 is a cross-sectional view taken along lines V—V of Figure 4; and

Figure 6 is a cross sectional view taken along lines VI—VI of Figure 4.

Referring more particularly to Figure 1, numeral 1 denotes the roof of an electric furnace, which roof has rigidly secured thereto a roof ring or skewback 2. The furnace roof is supported on cantilever or outrigger support beams 3 and 4 which are adjustably connected to the roof ring by suitable adjustable fastening means 5, 6, 7 and 8, for example, in the form of screw-threaded collar and post assemblies as will appear more clearly in Figure 2.

As will appear more clearly in Figure 3, the furnace crucible comprises a shell 9 lined internally with refractory material 10. The roof 1 likewise is lined internally with refractory material 11.

A cylinder 12 is rigidly attached to the furnace shell 9 by means of brackets 13 and 14. A cylindrical shaped ram 15 is adapted to be lifted in cylinder 12 by means of fluid or liquid pressure applied underneath the ram through port 16 to effect lifting of the roof 1. A collar 18, which carries a roller 17, is rigidly secured to the cylinder 12. A column eye bracket 19 is rigidly secured to ram 15 by means of screws 20 (see Figure 4) and has attached thereto and depending therefrom a shroud 18 having a cam groove 21 adapted to cooperate with roller 17. The roof 1 may be adjusted vertically with respect to eye bracket 19 by adjustable fastening means 5, 6, 7 and 8.

In operation, it will be apparent that when ram or cylinder 15 with the attached shroud 18 rises, the cam groove 21 moves up and around roller 17, causing both lifting and swinging of the eye bracket 19 to one side carrying with it the roof and electrode gear so as to uncover the furnace crucible. The crucible may then be conveniently charged by means such as a drop-bottom bucket loaded with scrap or other melting material.

The furnace is mounted on rockers 21 and 22 which roll on gear tracks 23 and 24, respectively, so as to be readily tiltable for tapping out the molten charge.

The arcing electrodes 25, 26 and 27 are carried by means of arms 28, 29 and 30, respectively, mounted on top of electrode rams 31, 32 and 33, respectively. These electrode rams slide

in fluid pressure cylinders 34, 35 and 36, respectively. As will appear more clearly in Figure 4, cylinder 15 is concentric with and slidably mounted in cylinder 12 and serves as a ram for the roof as well as a container for the electrode ram 33.

The electrode rams 31, 32 and 33 are all supplied with fluid pressure in a conventional manner through flexible hose connections (not shown) so that in any position of the roof the rams are 10 adjustably carried by the fluid pressure.

As stated previously, when cylinder 12 is fed with suitable pressure, ram 15 lifts and thus lifts and swings the roof to one side. The three electrode rams contained in cylinders 34, 35 and 36 are adjusted as required by the electric power arcs in the furnace in any well known manner by intermittently applying fluid pressure to lift the rams and carry with them the electrodes and their mountings. The electrode rams being carried by the same eye bracket 18, maintain their relationship thereto whenever the roof of the furnace is lifted and swung.

Referring to Figure 4, the ram or cylinder 15 is packed in cylinder 12 by "chevron" packing or other suitable packing material 38 held by a sealing ring 34 in any well known type of stuffing box. The ram 33 is similarly packed by means of a ring 34 and packing 38 in a conventional stuffing box as are the other similar rams 31 and 32. Ram or cylinder 15 is guided within the bore of cylinder 12 by means of slotted guides 39 and 40 sliding on guideways 41 and 42, respectively, so as to make it non-rotatable with respect to cylinder 15, in which it is further guided by means of bronze bushings 43.

The top end of electrode ram 33 as will appear in Figures 3 and 4 carries a bracket head 44, upon which is fastened a cradle 45 for supporting arm 38, which arm is water-cooled. At one end of arm 38 is supported a cylinder 46 which encloses a spring for normally urging lever 47 inwardly to cause a shoe or clamp 48 to be pressed against electrode 27, so as to firmly hold the electrode in a predetermined vertical position. Fluid pressure may be introduced in cylinder 46 on one side of a piston (not shown) to overcome the action of the spring so as to withdraw shoe 48 from electrode 27 to allow vertical adjustment of the electrode with respect to arm 38. The other electrode rams 31 and 32 carry similar electrode supporting structures as will be readily apparent from a study of Figures 1 and 3.

Two water core passages are provided, as shown in Figure 4, namely, 18^a and 18^b. Passage 18^a is a water cored passage in the beam core supporting casting 18 through which water is circulated for cooling purposes. The annular water passage 18^b is provided around the bezel ring 60 at the top of the furnace shell for conducting cooling water to prevent overheating in connection with the sand seal. The sand seal is provided by the bezel ring 60 which provides an L-shaped annulus 61 around the top of the furnace which is filled with sand or other refractory material into which the annular roof ring 11 seats to make the joint flamtight.

The specific structure of the electrode clamp and supporting means including the spring-operated, fluid pressure release cylinders, such as 46, forms the subject matter of my co-pending application entitled "Arc electrode support," filed January 31, 1946, under Serial No. 644,583.

In Figure 1, the full lines show the roof and associated electrode-supporting structure in a

5 normal position, whereas the dash and dot lines show these swung aside. Likewise in Figure 2 the dash and dot lines show the electrode supporting arms in a lifted position, whereas the full lines show them in a lowered position.

Thus it will be seen that I have provided a relatively simple mechanism for simultaneously swinging the roof and associated electrode-supporting structure aside as the roof is lifted by the ram. It will be apparent that the cam means for supporting structure is relatively simple in construction and foolproof in operation.

Also, it will be apparent that my invention is applicable to a furnace of the three electrode, three-phase type, or of the one electrode, single-phase type, or in fact, of any poly-phase type.

While I have illustrated and described a single embodiment of my invention, it will be understood that this is by way of illustration and that various changes and modifications may be made within the contemplation of my invention and within the scope of the following claims.

I claim:

1. An electric furnace of the top charge type including a crucible and roof and electrode supports, a ram cylinder rigidly secured to said crucible, a ram enclosed in said cylinder, bracket means rigidly secured to said ram for supporting said roof, said roof being liftable as the result of introduction of fluid in said cylinder beneath said ram, cam means associated with said cylinder to simultaneously effect sidewise swing of said roof during lifting thereof, said cam means including a depending skirt enshrouding said cylinder having a cammed groove and rigidly secured to said ram, a roller rigidly fastened to said cylinder and cooperable with said cammed groove to effect turning movement of said ram during reciprocation thereof, and said ram being hollow, a second ram slidably mounted in said first mentioned ram, and electrode support means mounted on said second ram.

2. An electric furnace of the top charge type including a crucible and a roof, bracket means secured to the walls of said crucible, beams secured by said bracket means for supporting the roof, a plurality of load-sustaining members adjustable vertically and longitudinally between the beams and the roof a hollow cylinder rigidly secured to said bracket means, a hollow ram reciprocable in said cylinder, a bracket rigidly secured to said ram and supporting said roof, a second ram reciprocable in said hollow ram, an electrode holder rigidly secured to said second ram thereby allowing relative movement between said electrode holder and said hollow ram.

3. An electric furnace comprising a crucible and roof, cantilever means for supporting the roof, vertically and longitudinally adjustable tensioning means between the roof and supporting means a ram cylinder rigidly secured to an outer wall portion of said crucible, a hollow ram reciprocable in said cylinder as the result of introduction therebeneath of fluid pressure, an eye bracket rigidly secured to said ram and supporting said cantilever means, a second ram reciprocable in said hollow ram, an electrode support carried by said second ram, and guide means secured to the inner walls of said hollow ram to prevent turning movement of said hollow ram during reciprocation thereof.

4. In an electric furnace having a roof, a support for said roof, a fluid pressure cylinder connected to said roof support for elevating said support to raise said roof, an electrode support car-

ried by said roof support, and a ram mounted concentrically within said cylinder and connected to the electrode support for moving said electrode support independently of said roof support.

5. In an electric furnace having a crucible and a roof therefor, a bracket supporting structure for said roof, a fluid pressure cylinder connected to the bracket supporting structure for actuating said bracket supporting structure to lift said roof with respect to said crucible, a plurality of electrode holders carried by said bracket supporting structure and movable therewith, fluid pressure operated rams connected to each of said electrode holders for operating each of said electrode holders independently of movement of said structure, and means mounting one of said fluid pressure operated rams concentrically of and within said cylinder.

6. In an electric furnace having a crucible and a roof therefor, a bracket supporting structure for said roof, a fluid pressure cylinder connected to said structure for actuating said bracket supporting structure to lift said roof with respect to said crucible, a plurality of electrode holders carried by said bracket supporting structure and movable therewith, means mounting each of said electrode holders on said bracket supporting structure including fluid pressure cylinders secured to and depending from said structure, and rams respectively in said last named cylinders and connected to said holders for moving said holders independently of movement of said supporting structure, and means mounting one of said last cylinders in said first fluid pressure cylinder whereby said one cylinder operates as a ram for effecting movement of said supporting structure.

7. In an electric furnace having a crucible and a roof therefor, a bracket supporting structure for said roof, a plurality of electrode holders, a plurality of fluid pressure cylinders secured to and depending from said structure, said cylinders occupying a position to one side of said crucible, a ram in each of said cylinders and connected to one of said holders for moving said holders independently of said supporting structure, and a stationary fluid pressure cylinder se-

cured to the crucible in which one of said plurality of cylinders is mounted whereby said one cylinder operates as a ram for moving said supporting structure to move the roof and all of said electrode holders.

8. In an electric furnace having a crucible and a roof therefor, a bracket supporting structure for said roof, an electrode holder, a first fluid pressure cylinder positioned to one side of the crucible and secured to and depending from said structure, a ram in said cylinder and connected to said holder for moving said holder independently of movement of said structure, and a second fluid pressure cylinder mounted in a relatively fixed position, said first cylinder being mounted in said second cylinder whereby said first cylinder operates as a ram for moving said supporting structure.

9. In an electric furnace having a crucible and a roof therefor, an electrode movable relative to the furnace, a bracket supporting structure for the roof, an electrode holder, a fluid pressure cylinder fastened to said structure, a cylinder fixedly secured to said crucible and in which the fluid pressure cylinder is received, and a ram concentrically arranged inside said fluid pressure cylinder and connected to the electrode holder.

WILLIAM E. MOORE.
